UNITED STATES PATENT OFFICE.

HERBERT O. RUSSELL, OF DETROIT, MICHIGAN, AND CHARLES LEIGH PAULUS, OF
• DAYTON, OHIO.

AUTOMATIC ADVANCE FOR SYNCHRONIZING GUN CONTROL.

Application filed March 2, 1922. Serial No. 540,507.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Automatic Advance for Synchronizing Gun Control, of which 10 the following is a specification.

This invention relates to an automatic advance for synchronized gun controls, the object in view being to provide means for automatically timing the firing impulses in the 15 Nelson gun control to compensate for any increase or decrease in the rotational speed of the engine shaft in order that the bullets will pass between the blades of the propeller and not damage the same.

With the above and other objects in view, the invention consists in the novel construction, combination and arrangement herein fully described, illustrated and claimed.

In the accompanying drawings; 25 Figure 1 is a side elevation of the device. Figure 2 is a diametrical section through the same.

Referring to the drawings, it will be seen that we divide the generator shaft into two 30 sections, 1 and 2, which are relatively adjustable in the manner hereinafter described. The shaft sections 1 and 2 are provided with spiral grooves or ways 3 and 4 and said grooves are reversely inclined with respect 35 to each other as illustrated in Figure 2. Surrounding the sections 1 and 2 of the generator shaft and overlapping both sections is a sliding sleeve 5 which is normally held in the position shown in Figures 1 and 2 by 40 means of a coiled spring 8 which encircles the sleeve and bears at one end against a collar 8' on the shaft section 2, said spring bearing at its upper end against a circumferential flange or annular shoulder 7' at the 45 upper end of the sleeve 5.

The sleeve 5 has on its inner side pins or 50 projections 6 and 7 which engage the grooves 3 and 4 of the shaft sections 1 and 2 so that as the sleeve is moved longitudinally of the generator shaft, one of the shaft sections will be advanced or retarded relatively to the other section according to the direction of movement of said sleeve.

The movement of the sleeve 5 is controlled

by a centrifugal governor. This governor 55 is shown as comprising diametrically opposite weighted arms 10 which are pivotally mounted at 11 on section 1 of the generator shaft and said weighted arms are provided with extension arms 12 which extend inwardly and bear against the sleeve 5 so that as the weighted governor arms swing outwardly as the speed of rotation of the shaft increases, they bear downwardly upon the sleeve 5 with the result above stated. 60

By the mechanism above described the timing of the firing impulses in the Nelson gun control is automatically increased in proportion to the increase in the rotational speed of the engine shaft. In other words, 70 as the speed of the engine shaft increases, the lead of the firing impulses is also increased, thereby preventing damage to the propeller blades.

Having thus described our invention, we 75 claim:

1. In synchronizing gun control, a rotary impulse generator shaft embodying axially aligned sections having reversely inclined grooves, and a centrifugally controlled 80 sleeve surrounding and slidable over the adjacent portions of the shaft sections and having projections operating in the grooves thereof to vary the lead of one shaft section relatively to the other. 85

2. In synchronizing gun control, a rotary impulse generator shaft embodying axially aligned sections having reversely inclined grooves, and a centrifugally controlled spring pressed sleeve surrounding and slid- 90 able over the adjacent portions of the shaft sections and having projections operating in the grooves thereof to vary the lead of one shaft section relatively to the other. 95

3. In synchronizing gun control, a rotary 95 impulse generator shaft embodying axially aligned sections having reversely inclined grooves, and a centrifugally controlled sleeve surrounding and slidable over the adjacent portions of the shaft sections and having means operating in the grooves thereof to vary the lead of one shaft section relatively to the other. 100

In testimony whereof we affix our signatures.

HERBERT O. RUSSELL,
CHARLES LEIGH PAULUS
